UNITED STATES PATENT OFFICE

155,811

DESIGN FOR AN ADJUSTABLE HANDBAG

Irma Kigere, New York, N. Y.

Application October 29, 1948, Serial No. 149,394

Term of patent 7 years

(Cl. D87—3)

To all whom it may concern:

Be it known that I, Irma Kigere, a citizen of the United States of America, residing in New York, county of New York, and State of New York, have invented a new, original, and ornamental Design for an Adjustable Handbag, of which the following is a specification, reference being had to the accompanying drawing, forming part thereof.

Fig. 1 is a front perspective view of an adjustable handbag, showing my new design.

Fig. 2 is a perspective view of the adjustable handbag showing the top, bottom and center insert in separated position;

Fig. 3 is a perspective view of the adjustable handbag with the center insert omitted.

Fig. 4 is a fragmentary view of the top of the handbag on a reduced scale, illustrating the handles.

The instant circular handbag is substantially the same in appearance all around.

I claim:

The ornamental design for an adjustable handbag, substantially as shown and described.
IRMA KIGERE.
